UNITED STATES PATENT OFFICE.

HUBERT JOSEPH BOEKEN, OF WELLINGTON, NEW ZEALAND.

APPARATUS FOR OBTAINING FIBER FROM FIBROUS PLANTS AND FOR TREATING THE SAME.

1,244,461.

Specification of Letters Patent. Patented Oct. 30, 1917.

Application filed May 14, 1915. Serial No. 28,225.

To all whom it may concern:

Be it known that I, HUBERT JOSEPH BOEKEN, a citizen of the Dominion of New Zealand, and residing at 35 Scarborough Terrace, Wellington, in the Provincial District of Wellington, in the Dominion of New Zealand, have invented certain new and useful Improvements in Apparatus for Obtaining Fiber from Fibrous Plants and for Treating the Same, of which the following is a specification.

This invention relates to machines used for obtaining fiber from fibrous plants, such as *Phormium tenax* (New Zealand flax), sisal, or pine apple leaves, and for preparing the fiber ready for the market, and provides a single apparatus wherein all the operations necessary for the above purpose are carried out.

Apparatus constructed according to my invention has two drums and their concaves located at a distance apart longitudinally and upon opposite sides of a conveyer rope or belt. Rim members upon the ends of the drums are adjustable radially without breaking the continuity of the rims, the rim on the side at which the fibrous leaves or fiber enters between the drum and the concave being overlapped by a rim or flange fixed to the frame of the machine and adjustable radially to correspond to the rim of the drum, and the rim on the side from which the fibrous leaves or fiber passes from the drum and concave overlapping the rim or flange fixed to the frame of the machine and being adjustable radially.

This latter rim is slotted and the teeth of a heckle project through the slot to comb the fiber after leaving the drum. The heckle is adjustable to comb long or short fiber and the rim has slides to adjust the slot to the altered position of the heckle.

The conveyer consists of a single endless rope or belt, whereon material to be treated is gripped while being treated, the material while being conveyed between the drums being dragged crosswise of the belt, whereby the whole length of the material is brought under treatment. The material is dragged crosswise of the belt by making a break therein by changing the direction of its travel from an approximately horizontal to a downward direction, and after returning the rope in a practically vertical and upward direction continuing the rope in an approximately horizontal direction and mov-

ing in the same direction as the previous horizontal part of the conveyer.

The grip upon the fiber is effected by passing the conveyer rope into grooves formed in gripper pulleys, the rims of the concave being higher than the rims at the bottom of the gripper pulleys. The rims of the concaves are located between the gripper pulleys and the drums. The fiber is thereby made to bend around the rim of the gripper pulley and around the rim of the concaves before it reaches the drums, and the grip is thereby considerably increased. The rims of the concaves are made adjustable, so that they may be raised or lowered to increase or decrease the grip, and the rim of each concave extends beyond each end of its drum for the purpose of securing an efficient grip upon the fiber before it reaches the drums, and of entirely withdrawing the fiber from the drums.

The drawings herewith illustrate the invention.

Figure 1 is a diagrammatic side elevation, Fig. 2, a plan, and Fig. 3, a sectional elevation on line A—A of Fig. 2.

Fig. 4, is a perspective view, and Fig. 5, a sectional plan of a drum fitted with my invention,

Fig. 6, is a cross sectional elevation on line B—B Fig. 7, and

Fig. 7, a sectional elevation of one end of a drum,

Fig. 8, a perspective view of a blade and its rim members,

Fig. 9, a perspective view of the end of a blade and its rim members,

Fig. 10, is a side elevation of the apparatus, and

Fig. 11, a sectional elevation on line C—C Fig. 10.

The single endless rope or belt conveyer 1 for conveying the material to be treated, passes beneath the gripper pulley 6, and around the guide pulley 2 mounted upon a shaft 3 to a guide pulley 4 at a lower level, and around a guide pulley 5 mounted upon the shaft 3, or on a separate shaft in line 105 with shaft 3. From the pulley 5 the rope passes beneath another gripper pulley 7 and around guide pulleys 8 and 9, either of which is a tension pulley.

A drum 8^a of ordinary construction and located on one side of the belt 1 operates in conjunction with a concave 9^a and treats one

part of the material 10 while gripped and hanging upon the said belt. From the pulley 6 the fiber passes to a director 12 consisting of an arm or apron attached to the 5 concave of the drum or other suitable part and shaped so as to guide over the pulley 5 the strands of fiber which have been treated by the drum 8^a.

The strands of fiber which have not been 10 treated by the drum 8^a including that part which was previously gripped between the pulley 6 and the conveyer 1 hang down from the conveyer after such treated strands of fiber have been conveyed beyond the 15 pulley 2.

The untreated strands are then treated by the drum 11 and its concave 12^a while the fibers are gripped between the pulley 7 and the conveyer 1.

20 Each of the concaves 9^a and 12^a is provided with an upper rim consisting of a plate 14 and a flange 15 whereby it is bolted to standards 16. The upper edge of the plate 14 is shaped to correspond to the circumference of the gripper pulley 7, and the plate 14 extends beyond the ends of the drum 8^a or 11 and is located between the gripper pulley 7 and the said drum.

The lower part of the rim of the pulley 7 30 is lower than the edge of the plate 14, so that the fiber 20 passes across the rim of the said pulley and over the edge of the plate 14, as shown in Fig. 11. The effect of kinking the fiber over the rim and plate 35 is that the hold upon the fiber is greatly increased.

By extending the plate 14 beyond each end of the drum, the fiber is brought on to the said plate and into position for treatment by the drum before the fiber is dragged 40 between the drum and its concave by the current of air set up by the drum, and until the fiber is removed from the sucking action of the drum.

45 The plate 14 is adjustable in height by inserting washers between the flange 15 and the standards 16. The vertical height of the plate 14 relatively to the rim of the pulley 7 can thus be regulated as required.

50 The disks 22 forming the ends of each drum 8^a and 11 are made with lugs 23 having slots 24 for the reception of the ends of ordinary beater blades 25 and for wings 26 of rim members 27.

55 Bolts 28 pass through slotted holes 29 formed in the lugs 23 and through holes in the blades and the said wings 26, the bolts fitting accurately in the holes of the blades and the wings 26.

60 The rim members 27 are made of plates bent to a right angle in cross section, the wings 26 being formed integral and at right angle to the backs of the rim members, or the wings may be attached to the said backs.

65 The rim members 27 completely surround

the rims of the disks 22 and are attached to the blades 25 by screws 33, and the ends of each rim member overlap the ends of adjacent rim members, the overlapping being in the same direction in each case, and so 70 that the forward end of each member is surmounted or covered by the rear end of its preceding member.

The ends of the rim members are fastened by bolts 34 passing through slotted holes 75 35 formed in the backs of the rim members.

The distance at which the blades are set from the surface of the concave determines the degree of intensity to which the fiber 80 is subjected to treatment.

When it is desired to alter the degree of intensity to which the fiber is being treated, the bolts 28 and 34 are slackened and the blades and rim members 27 are set radially 85 as desired, the slotted holes 29 permitting the rim members to expand or contract as required for assuming an alternation of circumference.

The rim members, on the end of the drum 90 from which the fiber passes out, overlap or surmount a correspondingly curved plate or flange 37 fixed to the frame 38 of the machine. A similar plate 39 fixed to the frame at the other end of the drum where the fiber 95 passes in is curved to correspond to the curve of the rim members, which the said plate overlaps, on the end of the drum.

By overlapping the plates and rim members in this manner, projecting edges of 100 plates, which would impede the passage of the fiber are avoided, and the fiber is prevented from getting to, and twining around, the drum shaft. This construction is clearly shown in Figs. 4 and 5.

105 The plates 37 and 39 are adjustable radially as required by means of washers 40 interposed between the said plates and the frame 38.

The plate 37 is also employed as part of 110 a heckling apparatus and for that purpose is provided with a slot 41, the opening of which can be adjusted by means of slides 42 made of plate and secured in any required position to the plate 37 by bolts 43.

115 A stud 44 adjustably fixed in a curved slot 45 formed in the frame 38 carries a pulley 46. The center of the curve of the slot 45 coincides with the center of the shaft 47 of the drum. A belt 48, carrying a plurality of projecting pins or spikes 49, passes around the pulley 46 and the shaft 47. The pins 49 project through the slot 41.

120 The belt 48 is driven by the shaft 47 and the pulley 46 is slowly rotated. The pins 125 49 comb the fiber after it has left the drum, removing short lengths and straightening out the fiber.

130 If long fiber is passing out of the machine, the pulley 46 is lowered and the slides 130

42 adjusted to correspond. If the fiber is short the pulley is raised.

What I do claim and desire to secure by Letters Patent of the United States is:—

5 1. In apparatus of the kind described, a conveyer consisting of a single endless rope or belt having an approximately horizontal part, a vertically downward part, a vertically upward part and a second horizontal 10 part, the horizontal parts overlapping between the vertical parts and the overlapping parts being spaced apart.

2. In apparatus of the kind described, a conveyer consisting of a single endless rope 15 or belt, a gripper pulley beneath which the rope passes, a guide pulley around which the rope passes, a second guide pulley to which the rope passes at a lower level, a third guide pulley around which the rope 20 passes to a pulley level with the first guide pulley, a second gripper pulley beneath which the rope passes, and guide pulleys beyond each of the gripper pulleys.

3. Apparatus of the kind described, comprising a single endless conveyer rope or belt passing around grooved pulleys, gripper pulleys having grooves into which the conveyer rope passes, fiber treating drums and concaves on opposite sides of the 30 conveyer rope, guide pulleys intermediate of the drums and whereby the conveyer rope is led from a practically horizontal direction to a downward direction and then in an upward direction and finally in a horizontal 35 direction so that a portion of the two horizontal parts of the conveyer rope overlap and are spaced apart at the same level or at approximately the same level, and an arm for guiding the fiber over the overlapping 40 part of the conveyer rope.

4. In apparatus of the kind described, a conveyer consisting of a single endless rope or belt, a gripper pulley beneath which the rope passes, a guide pulley around which the 45 rope passes, a second guide pulley to which the rope passes at a lower level, a third guide pulley around which the rope passes to a pulley level with the first guide pulley, a second gripper pulley beneath which the 50 rope passes, and guide pulleys beyond each of the gripper pulleys, either of which guide pulleys is a tension pulley.

5. In apparatus of the kind described, a drum and a gripper pulley, a concave member having its upper edge interposed between the gripper pulley and the drum, the said edge overlapping the rim of the bottom 55 of the gripper pulley.

6. In apparatus of the kind described, a 60 drum and concave member, the upper edge of the concave member being adjustable

vertically and a gripper pulley, mounted in a plane at right angles to the plane of said drum, and having its lower edge overlapping the upper edge of said concave member. 65

7. In apparatus of the kind described, a drum and a concave member, and a plate, forming the upper edge of the concave member having its ends extending beyond each 70 end of the drum in a direction parallel to the axis of said drum.

8. In apparatus of the kind described, a drum having blades adjustable radially, and a rim adjustable therewith. 75

9. In apparatus of the kind described, a drum having blades adjustable radially, and a rim adjustable circumferentially with the radial adjustment of the blades.

10. In apparatus of the kind described, a 80 drum having blades adjustable radially, a rim composed of overlapping members movable with the blades, the said members having slotted holes, and bolts passing through the slotted holes. 85

11. In apparatus of the kind described, a drum having ends composed of disks, lugs on the disks having radial slots adapted to receive the ends of the blades of the drum, rim members attached to the blades and having wings entering the said slots on each side of the blades, and bolts fitting holes in the blades and wings and passing through slotted holes in the lugs. 90

12. In apparatus of the kind described, a 95 drum having at one end a circumferential rim, a circumferential adjustable plate overlapped by the said rim, and another circumferential, adjustable plate concentric to the drum and overlapping the other end thereof. 100

13. In apparatus of the kind described, a drum and concave member, a plate concentric to the concave member, a rim on the drum overlapping the plate, and a heckle having pins projecting through a slot in the 105 plate.

14. In apparatus of the kind described, a drum, a shaft therefor and a concave member, a plate concentric to the concave member, a slot in said plate, slides adapted to 110 adjust the opening of said slot, a pulley projecting into the slot, a heckle band passing around the pulley and said shaft, and pins on said heckle band projecting through the slot, substantially as set forth. 115

In testimony whereof I have signed my name to this specification in the presence of two witnesses.

HUBERT JOSEPH BOEKEN.
